United States Patent Office

Des. 209,011
Patented Oct. 24, 1967

209,011

PORTABLE RADIATION DETECTOR

Mario Sollima, Colombes, Jean Guibourg, Bievres, and
Serge Lebèfaude, Vaucresson, France, assignors to Com-
pagnie Française Thomson Houston-Hotchkiss Brandt,
Paris, France, a corporation of France

Filed Apr. 11, 1966, Ser. No. 1,826

Claims priority, application France Oct. 15, 1965

Term of patent 7 years

(Cl. D52—6)

Fig.3

Fig.1

Fig.2

FIGURE 1 is a vertical elevational view from the dial side of an embodiment of the portable radiation detector having a large ionization chamber.

FIGURE 2 is a vertical elevational view, similar to FIGURE 1, of another embodiment of the radiation detector having a small ionization chamber.

FIGURE 3 is a top plan view of the embodiment of FIGURE 2.

FIGURE 4 is a bottom plan view of either embodiment.

FIGURE 5 is a vertical elevation of the embodiment of FIGURE 2, taken from the side opposite the dial, and

FIGURE 6 is an elevational view of the embodiment of FIGURE 2 from the front of the handle.

We claim:

The ornamental design for a portable radiation detector, as shown and described.
